UNITED STATES PATENT OFFICE

ERNEST STEVENSON, OF WEST HAVEN, CONNECTICUT, ASSIGNOR, BY MESNE ASSIGNMENTS, TO ELLIOTT-FISHER COMPANY, OF NEW YORK, N. Y., A CORPORATION OF DELAWARE

COMBINED TYPEWRITING AND COMPUTING MACHINE

Application filed July 18, 1925. Serial No. 44,451.

This invention relates generally to combined adding and typewriter machines, and is herein disclosed as applied to a machine of the Underwood-Hanson type in which indexing pins or devices are set up at the operation of the numeral-keys, and the numbers so indexed are subsequently run into a totalizer or register, an example of this class of machine being the well-known Underwood bookkeeping machine, which is illustrated in the patent to Minton, No. 1,280,065, dated September 24, 1918, and other patents.

In machines such as disclosed in said patent, the number-keys are effective, when the carriage reaches the computing zone, to set, by means of suitable key-setting mechanism, index-pins carried by pin-bars advanced one after another to effective position by denomination-selecting mechanism actuated by the carriage. When such selecting mechanism completes the indexing operation, the pin-bars and the usual number-wheels to which they are connected may be actuated by a general operator in accordance with the setting of the index-pins. Such denomination-selecting mechanism includes denominational jacks actuated by tappets moving with the carriage, and a series of thrust-rods or links driven by the denominational jacks are connected to the computing mechanism within a housing or case located beneath the typewriter. Machines of this character are usually made in two separable sections, namely, a typewriter-section and a computing-section, the latter including a case upon which the typewriter is detachably secured. It becomes necessary occasionally to remove the typewriter from the computing-case to gain access to the mechanism contained therein, and such removal requires detachment of the jack-driven thrust-rods.

Heretofore it has been the practice to attach the thrust-rods to the computing mechanism and to the typewriter by various means necessitating taking the rods off the machine before lifting the typewriter from the computing-case.

To overcome this disadvantage, the pres-

ent invention provides means whereby the thrust-rods may be readily released from their working position without taking them off, the rods being simultaneously shifted to a convenient position at the rear of the computing case and supported in such position.

One of the features of the present invention is the provision of a guide-frame for the thrust-rods, said frame being swingably mounted on the casing of the computing mechanism and normally swung to position to bring the thrust-rods in working position relatively to the denominational jacks. By thus swingably supporting the rods, they may be readily shifted to the rear of the machine where they are out of the way when lifting the typewriter from the computing case.

Another feature of the invention is the provision of clamping or holding means associated with the typewriter for detachably securing the guide-frame in position to render the jacks effective on the rods, the latter being automatically released from working position upon swinging the guide-frame free of its securing means.

A further feature of the invention is the provision of stop means for determining the position of the guide-frame when the same has been swung to position to free the thrust-rods from the typewriter.

Other features and advantages will hereinafter appear.

In the accompanying drawings, Figure 1 is a side elevation of a portion of the rear of an adding and computing machine disclosing the invention applied thereto, portions of the mechanism being broken away for clearness of illustration.

Figure 2 is a similar view, showing the thrust-rod guiding frame thrown backwardly to released position against a stop.

Figure 3 is a rear view of the denominational jacks and the guiding frame for the thrust-rods.

Figure 4 is a top plan view of Figure 2, with a portion of the jack-housing broken away to show the pin-receiving slots or clamps and the guideways for the thrust-rods.

In machines of the Underwood-Hanson type, the typewriter-carriage 10 is provided at its rear with one or more denomination-selectors 11 pivotally and slidingly mounted 5 on a rod 12 and usually held in adjusted position therealong by means of a notched rod 13. Each denomination-selector is normally in an ineffective depressed position, but as the carriage 10 in its letter-feeding 10 movement enters a computing zone, a cone-shaped roller 14 on the selector 11 will ride up on the tapered end of a zone-controlling roller 15 extending across the computing zone, and the denomination-selector 11 will 15 be elevated to effective position, as illustrated in Figure 1, so that a tappet 16, carried on the upper face thereof, may cam up one after another the forward ends 17 of denominational jacks 18 pivoted at 19 in a 20 housing 20, carried upon a bracket 21 fixed to the typewriter 22. The rear ends 23 of the jacks 18 overlie the upper ends 24 of thrust-rods or links 25, and upon actuation of the jacks 18 by the tappet 16, the thrust- 25 rods or links 25 will be depressed, and, through suitable mechanism, will advance the usual pin-carrying bars to pin-setting positions. The lower ends 26 of the thrust-rods 25 are usually provided with coupling- 30 heads 27 pivoted at 28 to the usual levers 29 extending through suitable openings in a casing 30, enclosing the computing mechanism, and the inner end of each lever 29 is operatively associated with the usual pin-carrying bars, not shown in the present application, but which may be of the character such as illustrated in the Minton patent 35 to which reference has been made.

Whenever it becomes necessary to remove 40 the typewriter 22 from the computing case 30, it is desirable to be enabled to quickly release the upper ends 24 of the thrust-rods 25 from their working position without the necessity of dismounting the thrust-rods 45 from their linkages. Applicant therefore provides a thrust-rod guide-frame 31 pivotally mounted at 32 between the arms 33 of a bracket 34 fixed to the outer face 35 of the casing 30 by any suitable means, such 50 as screws 36. The guide-frame 31 may include side plates 37 secured together by means of bridge-plates 38. The upper or free end of the guide-frame 31 has a connecting plate 39 extending between the inner 55 walls 40 of the side plates 37. The plate 39 is provided with a line of perforations 41 for the reception of the upper ends 24 of the thrust-rods 25, so that as the guide-frame 31 is swung forwardly or rearwardly about 60 its pivot 32, the thrust-rods 25 are carried therewith, and the upper ends of said rods are always maintained in alignment with one another by reason of the perforations 41. For holding the ends 24 of the thrust- 65 rods in working position beneath the jacks

18, there is provided a plate or shelf 42, having a pair of slots 43 forming resilient gripping fingers or clips 44. The bottom of each of the slots 43 may be cut away, as indicated at 45 to provide the requisite 70 resiliency for the clips 44. Pins 46, extending from the lower face 47 of the connecting plate 39, are received in the slots 43 when the guide-frame is swung to working position, and the gripping action of the resilient clips 44 effectively maintains the pins 46 within the slots 43, thus maintaining the upper ends 24 of the thrust-rods 25 in cooperative relation with their respective 75 jacks 18. The slots 43 are preferably rounded at 48 to conform to the shape of the pins 46, so that said pins are snapped into holding position by the resilient action of the gripping fingers or clips 44. It will be 80 readily understood that when the pins 46 are held in their respective slots, the free ends of the denominational jacks are in position to drive the thrust-rods 25 downwardly and thereby actuate the computing mechanism contained within the casing 30. 85 It will also be apparent that if for any reason it becomes necessary to remove the typewriter machine 22 from said computing casing, the guide-frame 31 may be swung rearwardly about its pivot 32 to disengage 90 the pins 46 from the slots 43, thus completely freeing the thrust-rods and guide-frame from the typewriter. It is desirable to provide means for limiting the rearward swing 95 of the guide-frame 31 in order to prevent 100 said guide frame from swinging too far away from the rear of the machine. For this purpose stops 49 are provided at the lower end of each of the side plates 37 beneath the pivot 32. Referring to Figure 105 2, it will be seen that upon swinging the guide-frame 31 outwardly, the stops 49 engage the outer face 35 of the computing casing 30 thus maintaining said guide-frame 31 in an upwardly inclined position, free 110 of the typewriter 22. The shelf 42 has notches 50 in the forward edge thereof for the reception of the rods 25. Upon swinging the guide-frame 31 to engage the pins 46 with the slots 44, the thrust-rods 25 are 115 entered in the notches 50.

In Figure 1 of the drawings, there is illustrated one type of fastening device which may be utilized as a means for detachably securing the typewriter to the computing case, although any other suitable means may be employed for this purpose as it forms no part of the present invention. Said fastening device may include a strap 51, having a lip 52 engaging the under face of a turned-in ledge 53 adjacent the top of the casing 30, the upper end of the strap having a setscrew 54 for engagement against the frame of the typewriter. A mounting section or base 55 is sometimes interposed between 120 125 130

the typewriter 22 and the computing case 30.

It will be seen that upon swinging the guide-frame 31 to the rear to release the thrust-rods 25, and unfastening the typewriter, the latter may be readily removed from the computing case, the thrust-rods being thus conveniently disposed in an inclined position at the rear of the computing case.

10 Variations may be resorted to within the scope of the invention, and portions of the improvements may be used without others.

Having thus described my invention, I claim:

- 15 1. In a combined typewriting and computing machine having a case for the computing mechanism and a typewriting machine detachably mounted thereon, and having a letter-feeding platen-carriage, and
- 20 carriage - actuated denomination - selecting mechanism including a plurality of denominational jacks, the combination with a plurality of rods having their lower ends connected to the computing mechanism of
- 25 a bracket fixed to the computing case, a frame pivoted on said bracket for swinging movement to or away from the typewriter, the upper end of the frame including means for detachably securing said frame to the
- 30 typewriter, and guide-means for the ends of the rods, whereby to maintain said ends in position to be actuated by the jacks, the lower end of said frame including extensions directed toward the computing case
- 35 below the pivot of said frame, so that when the latter is swung away from the typewriter, said extensions engage the face of said computing case and thereby limit the rearward swing of said frame.
- 40 2. In a typewriting and computing machine, a series of denominational jacks, a series of rods connected with the computing mechanism to be operated by the jacks, a bracket fixed to the casing of the comput-
- 45 ing mechanism near the lower ends of the rods, and a rack mounted parallel with the rods and pivoted to the bracket, effective to locate the upper ends of the rods with reference to the jacks.
- 50 3. In a combined typewriting machine and computing machine capable of being disassembled one from the other, a series of denominational jacks supported by the typewriting machine, a set of rods con-
- 55 nected with the computing machine, operable by the jacks, a swingable frame pivotally supported at its lower end by the computing machine, said frame having a disassembling rack at its upper end normally
- 60 spacing and holding the rods in alignment with said jacks, and means to secure the upper end of the frame to the typewriting machine to hold the rods in operating position with reference to the jacks when the
- 65 machines are assembled, said frame with

the entire set of rods forming a unit swingable outwardly from said operating position for disassembling.

4. In a combined typewriting machine and computing machine capable of being 70 disassembled one from the other, a series of denominational jacks supported by the typewriting machine, a set of rods connected with the computing machine, operable by the jacks, and a frame pivotally supported at 75 its lower end by the computing machine, means included in said frame to hold the rods spaced one from the other to correspond with the spacing of the jacks, and said means releasably securing said rods in operating position with reference to the jacks, said frame with the entire set of rods forming a unit swingable outwardly from said operating position for disassembling.

5. In a combined typewriting machine and 80 computing machine capable of being disassembled one from the other, a series of denominational jacks, a set of rods connected with the computing machine to be operated by the jacks, a disassembling 85 frame, pivoted at its lower end to said computing machine, substantially enclosing the rods throughout their length and a guide-rack forming the upper end of the frame perforated to receive the upper ends of the 90 rods and effective to guide the entire set into operative relation with their respective jacks, and out of operative relation therewith for disassembling.

6. In a combined typewriting and computing machine capable of being disassembled one from the other, a series of denominational jacks supported by the typewriting machine, a set of rods pivoted to the computing machine, operable by the 100 jacks, and a disassembling unit, swingable toward and outwardly from the typewriting machine, including a frame for housing the rods coextensive with the length thereof, said frame including a rack for spacing and 105 holding the upper ends of the rods, said frame having a pivotal connection near its lower end with said computing machine, the lower end of the frame forming a stop to move against the computing machine to 110 limit the outward disassembling swing of said unit.

7. In a combined typewriting machine and computing machine capable of being disassembled one from the other, a series of 115 denominational jacks, a set of rods pivoted to the computing machine and operable by said jacks, a movable disassembling frame to hold said rods and move the same into and out of operating position with reference to said jacks, and a stationary member, supported by said typewriting machine for aligning the rods with said jacks, including means for releasably securing the rods in 120 said operating position, said frame effec- 125

tive to swing the entire set of rods out of said operating position for disassembling.

8. In a combined typewriting machine and computing machine capable of being disassembled one from the other, a series of denominational jacks, a set of rods pivoted to the computing machine and operable by said jacks, a movable disassembling frame to hold said rods and move the same into and out of operating position with reference to said jacks, and a stationary plate, supported by and extending rearwardly from said typewriting machine, including means for spacing and aligning the rods with said jacks and including resilient clips engaging said frame for releasably securing the rods in said operating position, said frame effective to swing the entire set of rods out of said operating position for disassembling.

9. In a combined typewriting machine and computing machine capable of being disassembled one from the other, a series of denominational jacks, a set of rods pivoted to the computing machine and operable by said jacks, a movable disassembling frame to move the rods into and out of operating position with reference to the jacks, and a stationary plate, supported by said typewriting machine, having a notched surface to space the rods to correspond with the spacing of said jacks, the plate having resilient clips formed therein to releasably hold said frame, the frame being swingable from said clips to remove the rods from said operating position for disassembling.

ERNEST STEVENSON.
